(57) **CLAIM**

The ornamental design for a funnel, as shown and described.

DESCRIPTION

FIG. 1 is a top view of the funnel in accordance with my design;

FIG. 2 is a front view of the funnel shown in FIG. 1;

FIG. 3 is a rear view of the funnel shown in FIGS. 1-2;

FIG. 4 is a side view of the funnel shown in FIGS. 1-3; the opposite view being a mirror image thereof;

FIG. 5 is a bottom view of the funnel shown in FIGS. 1-4;

FIG. 6 is a perspective top view of the funnel shown in FIGS. 1-5; and,

FIG. 7 is a perspective bottom view of the funnel shown in FIGS. 1-6.

The broken lines shown in the drawing disclosure are for illustrative purposes only and form no part of the claimed design.
